UNITED STATES PATENT OFFICE.

JULIUS BRENZINGER, OF FAIRFIELD, CONNECTICUT, ASSIGNOR TO THE MAX AMS MACHINE COMPANY, OF BRIDGEPORT, CONNECTICUT, A CORPORATION OF NEW YORK.

SEAMING MACHINE.

Application filed January 27, 1925. Serial No. 5,018.

This invention relates to seaming machines, that is, machines for securing covers or bottoms to bodies.

In the art of seaming covers to bodies as heretofore practiced it has been the custom to move the seaming tool toward the work with a somewhat gradual motion, the seaming tool making a number of revolutions around the work or the work rotating a number of times while the seaming tool is moving inwardly in engagement with the work, and the deflection of the flange is therefore a gradual one and the full inward stroke of the seaming tool with respect to the work is not effected until near the end of the seaming operation.

This long-continued engagement of the seaming tool with the metal of the cover and body tends to change, adversely, the characteristics of the metal. Furthermore, especially when acting on non-circular bodies and covers, in certain types of seaming machines it is customary to so arrange the parts that during the time the seaming tool is moving toward the work certain gears are moving into mesh, the gears referred to being the ones that drive the seaming tool. It will be understood that if these gears engage gradually, rather than suddenly to their full extent, different speeds of the same parts will be obtained at different times during the seaming period owing to the different degree of intermeshing of the gears and this of course is disadvantageous.

The main object and feature of this invention is to overcome the above objectionable features so that the characteristics of the metal of the work may not be changed and so that the parts may be synchronized in their movements at all times, and the invention therefore consists of the features of construction, arrangement of parts and combination of elements a preferred form of which is disclosed in the accompanying description and drawings, in which latter:

Fig. 1 is a front elevation of a machine embodying the invention.

Fig. 2 is a side elevation thereof.

Fig. 3 is a rear elevation thereof.

Fig. 4 is a detail view in front elevation, on an enlarged scale, of one of the seaming roll bearings and adjacent parts.

Fig. 5 is a horizontal section on the plane of irregular line 5-5 of Fig. 4.

Fig. 6 is a horizontal sectional view on

the plane of line 6-6 of Fig. 3 showing, on an enlarged scale, the pneumatically-operated actuating device.

Fig. 7 is a transverse vertical sectional view on the plane of line 7-7 of Fig. 6. 60

Fig. 8 is an enlarged vertical sectional view on the plane of line 8-8 of Fig. 2.

Fig. 9 is an enlarged detail sectional view of some of the cams as viewed in the direction of arrow 9 of Fig. 3. 65

Fig. 10 is a detail sectional view of the first operation cam on the plane of line 10-10 of Fig. 3.

Suitable work holding means such as pedestal 1 and head 2 are provided between 70 which a can 3 with its cover 4 is placed. 5 and 6 indicate two seaming tools, 5 being the first operation tool and 6 the finishing tool. Each of these tools has a certain stroke moving it toward and away from the work, by suitable actuating means to be presently described, so arranged that each tool completes its stroke toward the work substantially at the beginning of its seaming operation. One revolution of the work 80 will therefore complete the seaming operation of one tool. 75

In the present case each seaming tool is carried by a seaming tool shaft 7 movably mounted and having at its lower end a gear 8 that is moved into and out of mesh with gear 9 moving with head 2. Inasmuch as the tool completes its inward stroke substantially at the beginning of its seaming operation one of the gears 8 and gear 9 are 90 brought fully into mesh substantially at the beginning of the seaming operation of a tool. 85

Any suitable actuating means such as a spring may be employed to quickly move a seaming tool toward the work but preferably a pneumatically-operated device is utilized on account of the quickness of its motion and also because of the yielding characteristic of its impulse. 95

The general arrangement of the machine to which the invention is in the present case applied is as follows:

10 is a main shaft having a suitable clutch 11 and a brake 12 both of which are actuated by lever 13 pivoted at 14 and so arranged that when the clutch is thrown in the brake is released and vice versa in a manner well understood. Shaft 10 carries two bevel gears 15 and 16 the former driving 105

110

115

bevel gear 17 of the pedestal drive and the latter meshing with bevel gear 18 driving upright shaft 19. At its upper end said upright shaft is provided with a bevel gear 5 20 that meshes with a bevel gear 21 on shaft 22 which latter carries a bevel gear 23 meshing with bevel gear 24 on shaft 25 carrying head 2. Shaft 19 also carries a worm 26 meshing with worm gear 27 on cam shaft 28. 10 7 indicates a seaming tool shaft, there being two such shafts in the present instance, each of said shafts being mounted as follows: Carried by the framework is a guide 29 having slots 30. 31 is a slide adjustable 15 in said guide and secured in position by means of a bolt 32 extending through slot 30. The slide carries trunnions 33 supporting a bearing 34 for shaft 7. Carried by the framework is another guide 35, for each 20 seaming tool shaft, in which guide is mounted a slide 36, said slide being confined by a gib 37. Suitably secured to slide 36 is a box 38 having trunnions 39 supporting a bearing 40 for shaft 7. Slide 36 is moved back 25 and forth from rockshaft 41 by means of suitable connections as 42 to thereby impart an in-and-out movement to shaft 7, said shaft pivoting around upper trunnions 33 and also moving about lower trunnions 39, 30 the extent of the rocking movement being limited by surfaces 43. 44 and 45 are stop surfaces limiting the movement of slide 36. Box 38 is adjustable on slide 36 by means of threaded member 46 freely rotatable in 35 extension 47 of slide 36 and in threaded engagement with box 38. At the upper end of shaft 7 is a gear 48 in constant mesh with gear 49 on shaft 25 and at the lower end of shaft 7 is a gear 8 moving in and out 40 of mesh with gear 9 also on shaft 25. It will be understood that gears 48 and 49 are for the purpose of maintaining gears 8 and 9 in such relative position that they can be thrown in and out of mesh; and it will be 45 further understood that the previously described adjustments of shafts 7 are used only when it is desired to substitute gears of different diameters as when changing from one size of can to another.

50 The pneumatically-operated actuating device is as follows: 50 and 51 indicate two cylinders carried by the framework one for each seaming tool. Sliding in each cylinder is a piston 52 having a connecting rod 53 connected to rock-shaft 41 by knuckle 54 and rod 55. Suitable valve means are provided here taking the following form: 56 indicates a valve rod having a reduced portion 57 and a head 58. This valve rod slides 55 60 in a passage 59 to which leads air inlet pipe 60 and from which there is an exhaust opening 61. 62 is a passage leading from cylinder 50 (or 51 as the case may be) to passage 59. It will be understood that if valve rod is 60 raised the exhaust opening 61 will be cov-

ered by a portion of said rod and head 58 will be elevated so as to establish communication between air inlet 60 and the cylinder, and that, conversely, if valve rod is lowered, into the position indicated in full 70 lines in Fig. 7, communication between the air inlet and the cylinder will be prevented and communication between the cylinder and exhaust opening 61 will be established. The pneumatic device is thus a single acting device and a spring 63 is used to move the piston in the other direction. As here constructed the pneumatically-operated device acts to move the seaming tool toward the work and the spring to retract it from 80 the work. It may be said here that the stroke of the piston should preferably be so adjusted with the stroke of shaft 7 that the seaming tool completes its inward movement against the work without slide 36 coming 85 into contact with stop 44. By these means a very quick and powerful blow is imparted by the seaming tool, said blow being at the same time cushioned to some extent by compressibility of the air or other fluid used. 90

The valve rods 56 are automatically controlled by suitable means which in the present instance are as follows: It will be understood that the two seaming tools do not act concurrently but one after the other. Therefore when the air is acting to advance one tool the other should be retracted. 64 and 65 indicate two cams on shaft 28. 66 and 67 indicate two rockshafts carrying bell cranks 68 and 69, the former connected by link 70 to valve rod of cylinder 50 and the latter connected by link 71 to valve rod of cylinder 51. The bell cranks carry cam rolls 72 and 73 that engage with cams 64 and 65 and these cams are so related circumferentially on shaft 28 that they act successively so that when one valve is open the other is closed. Springs as 74 may be used to force the cam rolls to follow the contour of the cams. 75 is a detent cam also mounted on shaft 28 and 76 is a pivoted detent or latch having roll 77 engaging with the detent cam. Detent cam 75 has two recesses 78 as shown and the timing, in the present instance is such that the work makes about three revolutions to a one-half revolution of shaft 28. Each of the cams 64 and 65 is also provided with two active cam surfaces as shown. Provision is preferably made whereby the latch is retracted from the detent cam and whereby at the same time the brake is released and the clutch is thrown in. When this happens therefore the parts begin rotation, the valve of the cylinder of the first operation roll is opened to admit air for about one revolution of the work after which the valve is closed and the exhaust opened; then the valve of the cylinder of the finishing roll is opened to admit air for about one revolution of the 100 105 110 115 120 125 130

work after which the exhaust is opened. Thus the seaming tools act successively. After the seaming cycle is completed cam 75 has brought its other recess adjacent roll 77 and simultaneously with this the clutch is withdrawn and the brake applied thus stopping the operation.

Provision is also preferably made whereby the same control mechanism that actuates the latch, brake and clutch also serves to lift and lower the pedestal and as here shown these parts take the following form:

Bevel gear 17 is loosely mounted on pedestal shaft 79, and said shaft is vertically movable in bearing 80. Mounted fast on shaft 79 is a collar 81 sliding on pins 82 carried by gear 17 whereby shaft 79 is rotated. Keyed on shaft 79 is a sleeve 83 and above said sleeve is a collar 84 fast to the shaft. Mounted on the sleeve are two collars one, 85, of which is fast to said sleeve and the other, 86, of which is loose on said sleeve. Interposed between the two collars 85 and 86 are cushion springs 87. 88 is a stationary bracket in which is pivotally supported at 89 a handle 90 connected by means of links 91 to sliding collar 86. When handle 90 is depressed links 91 lift collar 86 causing it to slide on sleeve 83 and when springs 87 have been sufficiently compressed against collar 85 sleeve 83 is elevated and, by reason of collar 84 fast on shaft 79, said shaft is likewise elevated. Two connections extend from handle 90, one, 92, connected to detent or latch 76, and another, 93, connected to brake and clutch lever 13. 94 indicates springs connected to handle 90 and bracket 88, and so long as the detent is held out by cam 75 the handle remains depressed and spring 94 is ineffective but as soon as a recess 78 permits the detent to drop inward springs 94 act to reverse the position of handle 90 thereby lowering the pedestal, throwing out the clutch and applying the brake.

I claim:

1. A seaming tool having a certain stroke toward and away from the work, and actuating means to cause said tool to complete its stroke toward the work substantially at the beginning of its seaming operation.

2. A seaming tool having a certain stroke toward and away from the work, and a pneumatically-operated actuating device to cause said tool to complete its stroke toward the work substantially at the beginning of its seaming operation.

3. A seaming machine including: rotatable work holding means, a gear carried thereby, a rotatable seaming tool shaft movable toward and away from the work, a seaming tool on the shaft to engage the work, a gear on the seaming tool shaft to engage and disengage the gear on the work holding means, and actuating means to move the shaft to cause the gear carried by said

shaft to fully engage the gear on the work holder substantially at the beginning of the seaming operation of the tool.

4. A seaming machine including a seaming tool, and means for moving the seaming tool toward and away from the work including: a cylinder, a piston, connections between the piston and tool, valve means controlling admission of fluid pressure to and exhaust from the cylinder, and a timed element to automatically open and close the valve means.

5. A seaming machine including a seaming tool, and means for moving the seaming tool toward and away from the work including: a cylinder, a piston, connections between the piston and tool, valve means controlling admission of fluid pressure to and exhaust from the cylinder, and a cam and connections to automatically open and close the valve means.

6. A seaming machine including a plurality of seaming tools, and means for moving the seaming tools sequentially toward and away from the work including: a pneumatically operated actuating device, valve means, and timed means to open and close the valve means.

7. A seaming machine including: a plurality of seaming tools, and means for moving the seaming tools sequentially toward and away from the work including: a pneumatically operated actuating device, valve means, and a plurality of cams and connections to automatically open and close the valve means.

8. A seaming machine including a plurality of seaming tools, and means for moving the seaming tools sequentially toward and away from the work including: a cylinder and a piston for each seaming tool, and connections between each seaming tool and its piston.

9. A seaming machine including a plurality of seaming tools, and means for moving the seaming tools sequentially toward and away from the work including: a cylinder and a piston for each seaming tool, connections between each seaming tool and its piston, and separate valve means for each cylinder controlling admission of fluid pressure to and exhaust from said cylinder.

10. A seaming machine including a plurality of seaming tools, and means for moving the seaming tools sequentially toward and away from the work including: a cylinder and a piston for each seaming tool, connections between each seaming tool and its piston, separate valve means for each cylinder controlling admission of fluid pressure to and exhaust from said cylinder, and a timed element for each valve means to automatically open and close said valve means.

11. A seaming machine including a plu-

rality of seaming tools, and means for moving the seaming tools sequentially toward and away from the work including: a cylinder and a piston for each seaming tool, connections between each seaming tool and its piston, separate valve means for each cylinder controlling admission of fluid pressure to and exhaust from said cylinder, and a cam and connections for each valve means to automatically open and close said valve means.

12. A seaming machine including a plurality of seaming tools, and means for moving the seaming tools sequentially toward and away from the work including: a cylinder and a piston for each seaming tool, connections between each seaming tool and its piston, separate valve means for each cylinder controlling admission of fluid pressure to and exhaust from said cylinder, a cam shaft, and cams on said shaft for sequentially and automatically opening and closing the valve means.

13. A seaming machine including a plurality of seaming tools, and means for moving the seaming tools sequentially toward and away from the work including: a cylinder and a piston for each seaming tool, connections between each seaming tool and its piston, separate valve means for each cylinder controlling admission of fluid pressure to and exhaust from said cylinder, a cam shaft, cams on said shaft for sequentially and automatically opening and closing the valve means, a detent cam also on said cam shaft, a latch, a clutch and a brake, and means for simultaneously withdrawing the latch from the detent cam and for operating the clutch and brake.

14. A seaming machine including: rotatable work-holding means, a seaming tool shaft pivotally supported at one end, constantly intermeshing gears on the work-holding means and the seaming tool shaft adjacent the point where the seaming tool shaft is pivoted, a seaming tool at the other end of the shaft, a guide adjacent said other end of the shaft, a slide movable in said

end of the shaft, a slide movable in said guide, a trunnion bearing in said slide supporting said shaft, a second gear movable with the work-holding means, a second gear on the shaft adjacent the seaming tool to engage and disengage with the second gear on the work-holding means, and means for moving the slide in the guide. 55

15. A seaming machine including: rotatable work-holding means, a seaming tool shaft pivotally supported at one end, constantly intermeshing gears on the work-holding means and the seaming tool shaft adjacent the point where the seaming tool shaft is pivoted, a seaming tool at the other end of the shaft, a guide adjacent said other end of the shaft, a slide movable in said guide, a trunnion bearing in said slide supporting said shaft, a second gear movable with the work-holding means, a second gear on the shaft adjacent the seaming tool to engage and disengage with the second gear on the work-holding means, and a pneumatically operated actuating device for moving the slide in the guide. 60 65

16. A seaming machine including: rotatable work-holding means, a seaming tool shaft pivotally supported at one end, constantly intermeshing gears on the work-holding means and the seaming tool shaft adjacent the point where the seaming tool shaft is pivoted, a seaming tool at the other end of the shaft, a guide adjacent said other end of the shaft, a slide movable in said guide, a trunnion bearing in said slide supporting said shaft, a second gear movable with the work-holding means, a second gear on the shaft adjacent the seaming tool to engage and disengage with the second gear on the work-holding means, and a pneumatically operated actuating device for moving the slide in the guide in one and a spring for moving it in the other direction. 70 75 80 85 90

Signed at Bridgeport, in the county of Fairfield and State of Connecticut, this 22nd day of January, 1925.

JULIUS BRENZINGER.
